VENTILATOR HOODS

Lester L. Miller, 2226 Rogero Road,
Jacksonville, Fla. 32211

Filed June 24, 1970, Ser. No. 23,649

Term of patent 14 years

Int. Cl. D23—04

U.S. Cl. D23—153

FIG. 1

FIG. 2

FIG. 5

FIG. 3

FIG. 6

FIG. 4

FIG. 7

FIG. 8

FIG. 11

FIG. 9

FIG. 12

FIG. 10

FIG. 1 is a front elevational view of a ventilator hood of my design embodied in a hood with screen;

FIG. 2 is a left side elevational view thereof;

FIG. 3 is a top plan view thereof;

FIG. 4 is a bottom view thereof;

FIG. 5 is a right side elevational view thereof;

FIG. 6 is a back side elevational view thereof;

FIG. 7 is a front elevational view of a ventilator hood of my design embodied in a hood without screen;

FIG. 8 is a left side elevational view thereof;

FIG. 9 is a top plan view thereof;

FIG. 10 is a bottom view thereof;

FIG. 11 is a right side elevational view thereof; and

FIG. 12 is a back side elevational view thereof.

I claim:

The ornamental design for ventilator hoods, substantially as shown and described.
